UNITED STATES PATENT OFFICE

146,546

DESIGN FOR A MATRIX ROLLER

George R. Steele, Battle Creek, Mich., assignor
to The Duplex Printing Press Company, Battle
Creek, Mich., a corporation of Michigan

Application May 23, 1946, Serial No. 130,018

Term of patent 14 years

(Cl. D64—11)

To all whom it may concern:

Be it known that I, George R. Steele, a citizen of the United States, residing at Battle Creek, county of Calhoun, State of Michigan, have invented a new, original, and ornamental Design for a Matrix Roller, of which the following is a specification, reference being had to the accompanying drawings, forming a part thereof.

In the drawings:

Fig. 1 is a side elevation of a matrix roller showing my new design.

Fig. 2 is an enlarged end view thereof.

Fig. 3 is a top plan view thereof.

I claim:

The ornamental design for a matrix roller, substantially as shown.

GEORGE R. STEELE.
